RAILWAY SIGNALING

George R. Pflasterer, Swissvale, Pa., assignor to
The Union Switch & Signal Company, Swiss-
vale, Pa., a corporation of Pennsylvania

Application April 17, 1936, Serial No. 74,876

16 Claims. (CL. 246—50)

My invention relates to railway signaling, and particularly to signaling involving wayside signals located along a trackway for governing the passage of trains.

5 A feature of my invention is the provision of novel and improved apparatus for establishing a distinctive control for each of three track sections in the rear of an occupied section. Each distinctive control is effective to cause a corresponding aspect of the associated wayside signal, whereby there is produced a three-block, four-indication, system of signaling.

10 The present invention is an improvement on the apparatus disclosed and claimed in an application Serial No. 68,807 for Letters Patent of the United States, filed March 14, 1936, by Leslie R. Allison, for Railway signaling, and in my application Serial No. 68,497, filed March 12, 1936, for Railway signaling.

15 20 I will describe one form of apparatus embodying my invention, and will then point out the novel features thereof in claims.

25 In the accompanying drawings, Figs. 1A and 1B are diagrammatic views which, when placed end to end in the order named, illustrate one form of three-block, four-indication, signaling system embodying my invention. Fig. 2 is a diagrammatic view illustrating a modification of a portion of Fig. 1A and also embodying my invention.

30 Similar reference characters refer to similar parts in each of the several views.

35 Referring first to Figs. 1A and 1B, the reference characters 7 and 8 designate the rails of a stretch of railway track along which traffic normally moves in the direction indicated by the arrows. The rails 7 and 8 are divided by insulated joints 9 into track sections W—X, X—Y, and Y—Z. As here shown, each track section is divided into 40 two subsections 1T, 2T, 3T, 4T, etc.

45 Each subsection is provided with a track battery 10 connected across the rails at one end of the subsection and with a track relay, designated by the reference character TR with a prefix the same as the numerical prefix of the associated subsection, connected across the rails at the other end of the subsection.

50 To govern the passage of trains through the stretch of railway, a wayside signal, designated by a suitable distinguishing reference character, is located at the entrance to each track section. As here shown, each signal is a color light signal comprising a green lamp G, a yellow lamp Y, and a red lamp R.

55 For controlling the signals, each section is pro-

vided with a direct current polarized signal control relay designated by the reference character HD with a prefix the same as the reference character of the associated signal.

5 Also for controlling the signals, each section is provided with a direct current relay of the well-known flasher type designated by the reference character F with a prefix the same as the reference character of the associated signal. Each flasher relay is provided with contacts which are normally biased to an initial deenergized position but which alternate between that position and a different position when the relay is energized. For example, relay 12F, when deenergized, maintains its contact 15—16 constantly closed 10 and its contact 17—18 constantly opened, but when the relay is energized, both contacts 15—16 and 17—18 alternate periodically between their closed and opened condition.

15 20 The contacts of each relay F function in the same manner as described for the contacts of relay 12F.

25 Each section is provided with a pair of line conductors each of which extends through the section to the signal next in advance and each of which includes a front contact of each of the track relays of the associated subsections.

30 35 Each relay HD is connected directly to the associated pair of line conductors and each relay F is connected to the associated pair of line conductors through an asymmetric unit, a transformer, and a resistor designated by the reference characters Q, M, and E, respectively, each with a prefix the same as the reference character of the associated signal.

40 The relatively high impedance of the relays HD will prevent the flow of alternating current in these relays and the transformers M will prevent the energization of the relays F by direct current. The resistors F are provided to prevent excessive flow of direct current in the primary windings of the transformers M.

45 It will be seen, therefore, that the relays HD will respond to direct current only and the relays F will respond to alternating current only.

45 50 Each section is provided with a suitable source of direct current here shown as a battery 40 with its terminals designated by the reference characters B and C.

50 55 Each section is also provided with a transformer, designated by the reference character N with a prefix the same as the reference character of the associated signal, and having a primary winding 19 and a secondary winding 20. The secondary winding 20 of each transformer N is

connected in series with the line circuit for the section next in rear so that when alternating current is supplied to the primary winding 19, alternating current will flow over the line circuit to control the relay F for the section next in rear.

For supplying alternating current to the primary winding 19 of the transformers N, each section is provided with a device, designated by the reference character A with a prefix the same as the reference character of the associated signal, for converting direct current into alternating current. As here shown, each device A is an alternator of the well-known tuned reed type. Referring to alternator 13A, for example, the reference character 21 designates a reed which is caused to vibrate between terminals 22 and 23 by a control winding 24. In the deenergized condition, reed 21 does not connect with either terminal 22 or terminal 23 but does connect with the terminal 25. When energy is supplied to the alternator 13A, winding 24 will attract reed 21 causing it to connect with terminal 23 and to move away from terminal 25, causing winding 24 to become deenergized. Upon the deenergization of winding 24, the resilience of reed 21 will cause it to move away from terminal 23 and to connect with terminal 22 as well as with terminal 25. The circuit for winding 24 will then be completed so that reed 21 again will go through the cycle of operation just described. Winding 24, therefore, will be repeatedly energized and deenergized as long as energy is supplied to its control circuit. When reed 21 connects with terminal 23, current is then supplied to the right-hand portion of primary winding 19 of transformer 13N; and when reed 21 connects with terminal 22, current is then supplied in the opposite direction to the left-hand portion of primary winding 19. Alternating current, therefore, will be induced in the secondary winding 20 of transformer 13N whenever alternator 13A is operating.

The alternator A for each of the other sections functions to supply alternating current to the associated transformer N in a manner identical to that described for alternator 13A.

Each section is provided with a pole changing relay having a slow releasing characteristic and designated by the reference character PC with a prefix the same as the reference character of the associated signal. As will be explained more in detail hereinafter, each relay PC is controlled by the associated relays HD and F in such a manner that the relays PC are energized whenever the associated relay HD is energized in the normal direction or whenever the associated relay F is energized provided the associated relay HD also is energized. Whenever the relays PC are energized, the line conductors for the section next in rear of the associated section are supplied with direct current in the normal direction. Whenever the relays PC are deenergized, such line conductors in the rear are supplied with direct current in the reverse direction and also with alternating current provided the associated polarized relay HD is then energized in the reverse direction.

Each of the color light signals is controlled by the associated relays HD, F, and PC in the following manner: When relay HD is deenergized (see signal 14), the red lamp R of that signal is lighted by a circuit which passes from terminal B through back point of contact 26 of relay 14HD, back contact 27 of relay 14PC, and lamp R to terminal C. Signal 14, therefore, is displaying a red light to indicate "stop". When relay HD is energized in

the reverse direction and relay F is deenergized (see signal 13), the yellow lamp Y of that signal is lighted by an uninterrupted circuit which passes from terminal B through front point of contact 28 of relay 13HD, reverse polar contact 29-30 of relay 13HD, constantly closed contact 31-32 of relay 13F, and lamp Y to terminal C. Signal 13, therefore, is displaying an uninterrupted yellow light to indicate "prepare to stop at next signal". When relay HD is energized in the reverse direction and relay F also is energized (see signal 12), the yellow lamp Y of that signal is lighted by an interrupted circuit which passes from terminal B through front point of contact 33 of relay 12HD, reverse polar contact 34-35 of relay 12HD, intermittently closed contact 15-16 of relay 12F, and lamp Y to terminal C. Signal 12, therefore, is displaying an interrupted or flashing yellow light to indicate "approach next signal at medium speed". When relay HD is energized in the normal direction (see signal 11), the green lamp G of that signal is lighted by a circuit which passes from terminal B through front point of contact 36 of relay 11HD, normal polar contact 37-38 of relay 11HD, and lamp G to terminal C. Signal 11, therefore, is displaying a green light to indicate "proceed at normal speed".

As here shown, a train K is indicated diagrammatically in the section immediately to the right of location Z so that relay 14HD is deenergized with the result that the relay 14PC also is deenergized.

Since relay 14PC is deenergized, relay 13HD is energized in the reverse direction over a circuit which passes from terminal B of battery 40 at signal 14, through back point of contact 41 of relay 14PC, secondary winding 20 of transformer 14N, front contact 42 of relay 6TR, front contact 43 of relay 5TR, relay 13HD, front contact 44 of relay 5TR, and front contact 45 of relay 6TR, and back point of contact 46 of relay 14PC to terminal C of battery 40.

When relay 13HD is energized in the reverse direction and relay 13F is deenergized, relay 13PC, of course, will remain deenergized. Since relay 13HD is energized in the reverse direction and relay 13PC is deenergized, the operation of alternator 13A is initiated by a circuit which passes from terminal B through front contact 47 of relay 13HD, reverse polar contact 48-49 of relay 13HD, back contact 50 of relay 13PC, and alternator A to terminal C.

Since relay 13PC is deenergized and alternator 13A is operating, relay 12HD is energized in the reverse direction and relay 12F also is energized. The circuit for relay 12HD may be traced from terminal B of battery 40 at signal 13 through back point of contact 51 of relay 13PC, secondary winding 20 of transformer 13N, front contact 52 of relay 4TR, front contact 53 of relay 3TR, relay 12HD, front contact 54 of relay 3TR, front contact 55 of relay 4TR, and back point of contact 56 of relay 13PC to terminal C. The circuit for relay 12F may be traced from one terminal of secondary winding 20 of transformer 13N through front contact 52 of relay 4TR, front contact 53 of relay 3TR, resistor 12E, transformer 12M, asymmetric unit 12Q, relay 12F, front contact 54 of relay 3TR, front contact 55 of relay 4TR, back point of contact 56 of relay 13PC, battery 40 at signal 13, and back point of contact 51 of relay 13PC to the other terminal of secondary 20 of transformer 13N.

Since both relays 12HD and 12F are energized, 75

relay 12PC is energized over a circuit which passes from terminal B through contact 17-18 of relay 12F, front contact 57 of relay 12HD, and relay 12PC to terminal C. Although the contact 17-18 of relay 12F will be alternately closed and opened, the slow releasing characteristic of relay 12PC will prevent this relay from dropping away during the open circuit periods.

Since relay 12PC is energized, relay 11HD is energized in the normal direction over a circuit which passes from terminal B of battery 40 at signal 12 through front point of contact 58 of relay 12PC, front contact 59 of relay 2TR, front contact 60 of relay 1TR, relay 11HD, front contact 61 of relay 1TR, front contact 62 of relay 2TR, secondary winding 20 of transformer 12N, and front point of contact 63 of relay 12PC to terminal C.

Since relay 11HD is energized in the normal direction, relay 11PC also is energized over a circuit which passes from terminal B through front contact 64 of relay 11HD, normal polar contact 65-66 of relay 11HD, and relay 11PC to terminal C. When relay 11PC is energized, the line circuit for the section next in rear of location W will be supplied with direct current in the normal direction so that the signal (not shown) controlled by such rear line circuit will be displaying the normal proceed indication.

Summing up then, it will be seen that when a section is occupied by a train, the signal for that section will display a red light to indicate "stop", the signal for the section next in rear will display an uninterrupted yellow light to indicate "approach next signal prepared to stop", the signal for the second section in rear will display a flashing yellow light to indicate "approach next signal at medium speed", and the signal for the third section in rear will display a green light to indicate "proceed at normal speed". The apparatus embodying my invention, therefore, provides four distinctive indications with the use of the usual three unit color light signal.

The slow releasing characteristic of the relays 45 PC will prevent tumble-down of the signal control circuits to the rear during pole changing periods. For example, when the train K passes out of the section to the right of location Z so that relay 12HD becomes energized in the normal direction to cause signal 12 to display the normal proceed indication, current will be momentarily disconnected from relay 12PC during the time this relay is being transferred from control by contact 17-18 of relay 12F and front contact 57 of relay 12HD to control by front contact 69 and normal polar contact 91-92 of relay 12HD. During this period, however, front points of contacts 58 and 63 of relay 12PC will not become opened so that the energization of the line 60 circuit for the section W-X will not be disturbed.

The control of the red lamp R by a back contact of the associated relay PC also prevents a momentary flash of the red lamp during pole changing periods. For example, back contact 67 of relay 12PC does not become closed during the pole changing period mentioned above even though back point of contact 33 of relay 12HD does become momentarily closed. The red lamp R, therefore, cannot become lighted during the changes of polarity in the energization of the associated control relay HD.

Referring now to Fig. 2, the reference character H designates a direct current polarized signal control relay having a retained neutral char-

acteristic. The relay H is connected directly to the pair of line conductors in the same manner as described for the relay HD shown in Figs. 1A and 1B.

The reference character J designates a direct current neutral relay which is connected to the line conductors by a resistor E, a transformer M, and an asymmetric unit Q in the same manner as described for the relay F shown in Figs. 1A and 1B.

The relay F is a flasher relay of the type employed in the system shown in Figs. 1A and 1B and is controlled by a front contact 70 of the relay J and, therefore, will be energized or de-energized according as the relay J is energized or deenergized.

The signal and associated apparatus shown in Fig. 2, when connected in a system, will function to provide a three-block, four-indication, signaling in a manner similar to that described for the signals and associated apparatus shown in Figs. 1A and 1B.

Since the relay H is provided with a retained neutral feature, the slow releasing pole changing relay PC is no longer required to insure against tumble-down of the signal control circuits to the rear during pole changing periods or to prevent a momentary flash of the red lamp during such periods.

The relays H and F control the signal lamps in the following manner: When the relay H is deenergized, the red lamp R of the signal will be energized by a circuit which passes from terminal B through back point of contact 71 of relay H and lamp R to terminal C so that the signal will display a red light to indicate "stop." When the relay H is energized in the reverse direction, and relay J is deenergized so that relay F also is deenergized, the yellow lamp Y will be energized by an uninterrupted circuit to cause the signal to display a steady yellow light to indicate "approach next signal prepared to stop." This circuit may be traced from terminal B through front point of contact 71 of relay H, reverse polar contact 72-73 of relay H, constantly closed contact 74-75 of relay F, and lamp Y to terminal C. When the relay H is energized in the reverse direction, and relay J is energized so that relay F also is energized, yellow lamp Y will be energized by an interrupted circuit to cause the signal to display a flashing yellow light to indicate "approach next signal at medium speed." This circuit may be traced over the same path as previously described for the yellow lamp, the only difference being that contact 74-75 of relay F will be alternately opening and closing whereas when the relay F is deenergized, contact 74-75 will remain constantly closed. When relay H is energized in the normal direction as shown in the drawings, the green lamp G is energized over a circuit which passes from terminal B through front point of contact 71 of relay H, normal polar contact 72-76 of relay H, and lamp G to terminal C so that the signal is displaying a green light to indicate "proceed at normal speed."

The relays H and J control the current supplied to the line circuit for the section next in rear in the following manner: When relay H is deenergized, the line conductors for the section next in rear will be supplied with direct current energy in the reverse direction over back points of contacts 71 and 78 of relay H.

When relay H is energized in the reverse direction and relay J is deenergized, the operation of

alternator A will be initiated and the line conductors for the section next in rear will be supplied with alternating current simultaneously with direct current in the reverse direction. The 5 circuit for alternator A may be traced from terminal B through back contact 79 of relay J, front contact 80 of relay H, reverse polar contact 81—82 of relay H, and alternator A to terminal C. The direct current for the line conductors 10 in the rear will be supplied from battery 40 over a path including back points of contacts 83 and 84 of relay J, reverse polar contacts 85—86 and 87—88 of relay H, and front points of contacts 77 and 78 of relay H, and alternating current 15 will be supplied to such conductors over the same path from secondary winding 20 of transformer N.

When relay H is energized in the reverse direction and relay J also is energized, the line conductors for the section next in rear will be supplied with direct current in the normal direction 20 over front points of contacts 83 and 84 of relay J, reverse polar contacts 85—86 and 87—88 of relay H, and front points of contacts 77 and 78 of relay H.

25 When relay H is energized in the normal direction, the line conductors for the section next in rear will be supplied with direct current in the normal direction over normal polar contacts 89—87 and 90—85 of relay H, and front points 30 of contacts 77 and 78 of relay H.

From the foregoing description of the two modifications of apparatus embodying my invention, it will be apparent that I have provided a three-block, four-indication, system wherein only 35 two line conductors are required from signal to signal and wherein the usual three-indication unit color light signal may be utilized without adding additional indication units. Furthermore, my system requires no source of commercial 40 alternating current and is economical in current consumption since alternating current is converted from the usual source of direct current only when traffic conditions are such as to require the display of a flashing yellow light.

45 Although I have herein shown and described only one form of apparatus embodying my invention, it is understood that various changes and modifications may be made therein within the scope of the appended claims without departing 50 from the spirit and scope of my invention.

Having thus described my invention, what I claim is:

1. In combination, a section of railway track, a pair of line conductors for said section, means 55 governed in accordance with traffic conditions in advance of said section for supplying said pair of conductors with current of one character or with current of another character simultaneously with current of said one character or with 60 current of still a different character, a signal for said section including a first lamp and a second lamp, and means receiving energy from said pair of conductors for governing said lamps whereby only the first lamp is energized steadily 65 if said conductors are supplied with current of said one character or only the first lamp is energized periodically if said conductors are supplied with current of said other character simultaneously with current of said one character or 70 only the second lamp is energized if said conductors are supplied with current of said different character.

2. In combination, a section of railway track, a pair of line conductors for said section, means 75 governed in accordance with traffic conditions in

advance of said section for supplying said conductors with direct current only or with alternating current simultaneously with direct current, a signal for said section including a lamp, and means receiving energy from said conductors 5 for governing said lamp whereby the lamp is energized steadily if direct current only is supplied to the conductors or is energized periodically if alternating current is supplied simultaneously with direct current to said conductors. 10

3. In combination, a section of railway track, a signal for said section including a first lamp and a second lamp, a first signal control relay and a second signal control relay, means governed in accordance with traffic conditions in advance of said section for energizing only said first relay in one direction or for energizing said second relay simultaneously with the energization of said first relay or for energizing only said first 15 relay in the other direction, a circuit for said first lamp which becomes steadily energized when only said first relay is energized in said one direction but which becomes periodically energized when both said relays are energized, and a circuit for said second lamp which becomes energized only when said first relay is energized in said other direction. 20

4. In combination, a section of railway track, a signal for said section including a first lamp and a second lamp, a first signal control relay 30 and a second signal control relay, means governed in accordance with traffic conditions in advance of said section for energizing only said first relay in one direction or for energizing said second relay simultaneously with the energization 35 of said first relay or for energizing only said first relay in the other direction, a flasher relay which becomes energized when said second relay is energized, a circuit for said first lamp which becomes steadily energized when only said 40 first relay is energized in said one direction but which becomes periodically energized when both said first relay and said flasher relay are energized, and a circuit for said second lamp which becomes energized only when said first relay is 45 energized in said other direction.

5. In combination, a section of railway track, a signal for said section including a first lamp and a second lamp, a signal control relay and a flasher relay, means governed in accordance with 50 traffic conditions in advance of said section for energizing only said signal control relay in one direction or for energizing said flasher relay simultaneously with the energization of said signal control relay or for energizing only said signal 55 control relay in the other direction, and means controlled by said two relays for governing said lamps whereby the first lamp is energized steadily if only said signal control relay is energized in said one direction or is energized periodically 60 if both said relays are energized and said second lamp is energized if said signal control relay is energized in said other direction.

6. In combination, a section of railway track, a signal for said section including a first lamp 65 and a second lamp, a signal control relay and a flasher relay, means governed in accordance with traffic conditions in advance of said section for energizing only said signal control relay in one direction or for energizing said flasher relay simultaneously with the energization of said signal control relay or for energizing only said signal 70 control relay in the other direction, a circuit for said first lamp including contacts of both relays whereby the first lamp is energized steadily if 75

only said signal control relay is energized in said one direction but is energized periodically if both said relays are energized, and means for energizing said second lamp effective only if said signal control relay is energized in said other direction.

7. In combination, a section of railway track, a polarized relay for said section and a flasher relay for said section, means for deenergizing both said relays when said section is occupied, means for energizing only said polarized relay in the normal direction or for energizing only said polarized relay in the reverse direction or for energizing said flasher relay simultaneously with the energization of said polarized relay in the reverse direction, a signal for said section including a red and a yellow as well as a green lamp, a circuit for said red lamp including a back contact of said polarized relay, a circuit for said yellow lamp including a front contact of said polarized relay and a reverse polar contact of said polarized relay as well as a contact of said flasher relay, and a circuit for said green lamp including a front contact of said polarized relay and a normal polar contact of said polarized relay.

8. In combination, a section of railway track having a track circuit including a track relay, a pair of conductors for said section each including a contact of said track relay, a polarized direct current line relay connected to said pair of conductors, a flasher line relay receiving energy from said conductors through an asymmetric unit, means governed in accordance with traffic conditions in advance of said section for supplying said conductors with only direct current of one polarity or with alternating current simultaneously with direct current of said one polarity or with only direct current of the other polarity, and a signal lamp for said section governed by said two line relays whereby said lamp is constantly energized when said line conductors are supplied only with direct current and is energized periodically when said line conductors are energized with alternating current simultaneously with direct current.

9. In combination, a section of railway track having a track circuit including a track relay, a pair of conductors for said section each including a contact of said track relay, a polarized direct current line relay connected to said pair of conductors, a direct current neutral relay, means including an asymmetric unit for connecting said neutral relay to said conductors, a flasher relay governed by said neutral relay, means governed in accordance with traffic conditions in advance of said section for supplying said conductors with only direct current of one polarity or with alternating current simultaneously with direct current of said one polarity or with only direct current of the other polarity, and a signal for said section governed by said polarized relay and by said flasher relay.

10. In combination, a forward section and a rear section of railway track, a signal for the forward section, a signal control relay and a flasher relay governed by traffic conditions in advance of said forward section for governing said signal, another relay governed by said two relays, and a signal control circuit for the rear section governed by said other relay.

11. In combination, a section of railway track, a pair of conductors for said section, means for selectively supplying said pair of conductors with currents of three different characters respectively in accordance with traffic conditions in advance of said section, a signal for said section including

a first lamp and a second lamp, and means selectively responsive to said three characters of current for lighting said first lamp steadily or said first lamp periodically or said second lamp whereby said signal is caused to display three distinctive indications to correspond to said three characters of current.

12. A railway signaling system comprising a stretch of railway track divided into sections, a pair of conductors for each section, means for each section for supplying the associated pair of conductors with currents of three different characters respectively in accordance with traffic conditions in advance of such section, a signal for each section, and means for each section selectively responsive to said three characters of current for controlling the associated signal in such a manner that said signal is caused to display a steady light of one color or a flashing light of said one color or a light of a different color to correspond to said three characters of current respectively.

13. A railway signaling system comprising a stretch of railway track divided into sections, a pair of conductors for each section governed by traffic conditions in that section, means for each section for supplying the associated pair of conductors with currents of three different characters respectively in accordance with traffic conditions in advance of such section, control means for each section capable of assuming one condition when the associated section is occupied and three other distinctive conditions to correspond to said three characters of current when the associated section is unoccupied, and a signal for each section governed by the associated control means in such a manner that said signal is caused to display a light of one color or a steady light of another color or a flashing light of said other color or a light of still a different color to correspond to the four conditions of said control means.

14. In combination, a stretch of railway track divided into a plurality of successive block sections each having a pair of conductors governed by traffic conditions in said section, a signal for each section comprising a plurality of lamps, a polarized direct current relay for each section energized from the conductors for such section and selectively controlling circuits through which current may be supplied to the lamps of the signal for such section, a control relay for each section energized from the conductors for such section, said control relay being responsive only to alternating current supplied to said conductors, means controlled by said control relay and operative only when said control relay is energized to periodically establish and interrupt the circuit for supplying current to at least one of the lamps of the signal for such section, the polarized relay associated with each block section controlling the supply of alternating current to the conductors of the adjacent block section in the rear, the polarized relay and the control relay for each block section jointly controlling the supply of direct current to the conductors of the adjacent block section in the rear.

15. In combination, a stretch of railway track divided into a plurality of successive block sections each having a pair of conductors governed by traffic conditions in said section, a signal for each section comprising a plurality of lamps, a polarized direct current relay for each section energized from the conductors for such section and selectively controlling circuits through which

- current may be supplied to the lamps of the signal for such section, a control relay for each section energized from the conductors for such section, said control relay being responsive only to 5 alternating current supplied to said conductors, means controlled by said control relay and operative only when said control relay is energized to periodically establish and interrupt the circuit for supplying current to at least one of the lamps 10 of the signal for such section, each block section having associated therewith an alternating current generator operative on the supply of direct current to supply alternating current to the conductors of the adjacent block section in the rear, 15 the polarized relay associated with each block section controlling the supply of direct current to the alternating current generator for such block section, the polarized relay and the control relay for each block section jointly controlling the supply 20 of direct current to the conductors of the adjacent block section in the rear.
16. In combination, a stretch of railway track divided into a plurality of successive block sections each having a pair of conductors governed
- by traffic conditions in said section, a signal for each section comprising a plurality of lamps, a polarized direct current relay for each section energized from the conductors for such section and selectively controlling circuits through which 5 current may be supplied to the lamps of the signal for such section, a control relay for each section energized from the conductors for such section, said control relay being responsive only to alternating current supplied to said conductors, 10 the polarized relay associated with each block section controlling the supply of alternating current to the conductors of the adjacent block section in the rear, the polarized relay and the control relay for each block section jointly controlling 15 the supply of direct current to the conductors of the adjacent block section in the rear, and means controlled by one of said relays for each block section for periodically establishing and interrupting a circuit through which current may 20 be supplied to at least one of the lamps of the signal for such block section.

GEORGE R. PFLASTERER.
